INDUSTRIAL GAUGING HEAD WITH TRAVERSING MOUNT FOR DETECTING SHEET MATERIAL PROPERTIES

John H. Schlaechter, Columbus, Ohio, assignor to Industrial Nucleonics Corporation, a corporation of Ohio

Application October 17, 1957, Serial No. 48,140

Term of patent 14 years

(Cl. D52—1)

Fig. 1 is a perspective view of an industrial gauging head with traversing mount for detecting sheet material properties showing my new design,

Fig. 2 is a section on lines 2—2 of Fig. 1, and

Fig. 3 is a fragmentary perspective view thereof taken at a different angle from that of Fig. 1.

I claim:

The ornamental design for an industrial gauging head with traversing mount for detecting sheet material properties, as shown.
